POST MEMBER FOR A DOOR SECTION

J. Kenneth Rimington, 10562 109th St., Edmonton,
Alberta, Canada

Filed Sept. 1, 1967, Ser. No. 8,467

Term of patent 14 years

U.S. Cl. D13—6
Int. Cl. D25—03

FIGURE 1 is a perspective view of a portion of a post member for a door section showing my new design;

FIGURE 2 is an end view of the post member for a door section shown in FIGURE 1;

FIGURE 3 is a top plan view of the post member for a door section shown in FIGURE 1;

FIGURE 4 is a bottom plan view of the post member for a door section shown in FIGURE 1;

FIGURE 5 is a right side elevational view of the post member for a door section shown in FIGURE 1; and

FIGURE 6 is a left side elevational view of the post member for a door section shown in FIGURE 1.

The characteristic features of my design for a post member for a door section resides in the combination of each of said serrated flanges being closely disposed adjacent a corresponding side of said post member, each relatively short flange disposed normal to each serrated flange being located closer to the free end of said serrated flange than the other end thereof, and the flange extending from

the other side of said post member in a direction opposite to the direction of extension of said serrated flanges being generally parallel with said serrated flanges and intermediate thereof.

I claim:

The ornamental design for a post member for a door section, as shown and described.
